UNITED STATES PATENT OFFICE.

HENRY O'MEARA, OF SIOUX FALLS, SOUTH DAKOTA.

ACETYLENE-GAS GENERATOR.

1,111,230.

Specification of Letters Patent. Patented Sept. 22, 1914.

Application filed March 19, 1914. Serial No. 825,841.

To all whom it may concern:

Be it known that I, HENRY O'MEARA, a citizen of the United States, residing at Sioux Falls, in the county of Minnehaha and State of South Dakota, have invented certain new and useful Improvements in Acetylene-Gas Generators; and I do declare the following to be a full, clear, and exact description of the invention, such as will enable others skilled in the art to which it appertains to make and use the same.

This invention relates to improvements in acetylene gas generators and the primary object of the invention is to provide a simply 15 constructed generator of the herein described character, which will be efficient and reliable in operation.

A secondary object is to provide simple and efficient means, operated by the descent 20 of the gas bell, for opening the valve in the carbid hopper, thereby allowing a new charge of carbid to enter the generating chamber.

Still another object is to provide a structure 25 whereby the tube which conducts the carbid from the hopper to the generating chamber, acts also as a gas discharge pipe.

With the above objects in view, the invention resides in certain novel features of 30 construction and combination herein described and claimed and shown in the drawings wherein—

Figure 1 is a vertical section of my improved generator; Fig. 2 is a vertical section 35 taken at right angles to Fig. 1 and on substantially the line 2—2 of said figure, the hopper and bell being shown in elevation; Fig. 3 is an enlarged vertical section through the carbid hopper and the discharge pipe therefrom, the valve in said 40 hopper being closed. Fig. 4 is a detail horizontal section on the line 4—4 of Fig. 5; and Fig. 5 is a vertical section taken on the line 5—5 of Fig. 3.

In the accompanying drawings, I have 45 shown my improved generator as comprising, in general, a water tank 1, a gas bell 2, a carbid hopper 3 and various connections for controlling the feed of the carbid and 50 for also receiving the gas generated.

The water tank 1 is preferably cylindrical and is open at its upper end, while its lower end is closed by a solid bottom 4. Spaced a suitable distance from said bottom 55 4 is a horizontal partition 5 having its central portion bulged upwardly as at 6

and in communication with the interior of an upright pipe 7. This pipe 7 has a two-fold function of conveying carbid to the space between the bottom 4 and the partition 5 and of conducting the gas generated in said space to the house connection or service pipe.

As clearly shown in the drawings, the bell 2 is of cylindrical contour and is provided with a solid top 8, while its lower end is entirely open as is common with devices of this character. The top 8 of the bell is provided with a central opening 9 within which a sleeve 10 is rigidly secured, said sleeve surrounding the pipe 7 and having its lower end flared outwardly as at 11. Thus it will be seen that the pipe 7 acts also as a guide for the bell 2 in its ascent and descent. The top 8 of the bell 2 is also provided with an eccentric opening 12 from which a small cylinder 13 rises, said cylinder being closed at its upper end and provided with a suitable loop or eye 14, the function of which will hereinafter appear.

In addition to the hereinbefore set forth uses of the pipe 7, it also forms a rigid support for the carbid hopper 3. Said hopper comprises a funnel shaped lower end 15 which is in communication with the interior of the pipe 7, and is provided with an upright wall 16 at its upper edge. The upper edge of the wall 16 is provided with a cover 17, the latter having a threaded filling opening 18 which is normally closed by a screw cap 19. Within the hopper 3 and disposed in vertical alinement with the pipe 7, is a substantially cylindrical guide 20 which, as shown, is closed at its upper end while its lower end is entirely open and is spaced from the junction of the lower end 15 of the hopper 3, with the pipe 7. The guide 20 may be rigidly secured in this position in any suitable manner, a sleeve 21, leading from said guide 20 through the wall 16, usually answering this purpose. The outer end of the sleeve 21 is externally threaded and engaged with internal threads in a boss 22 formed on the outer side of the wall 16, said outer end of the tube being provided with an annular collar 21' which contacts with the inner side of said wall. As clearly seen in Fig. 3, the boss 22 receives, in its outer end, a packing nut 22' between which and the adjacent end of the tube 21, a packing ring is located, the adjacent ends of said tube and said nut being countersunk

to force said packing ring into engagement with a shaft 23 which is located in said tube and is provided on its inner and outer ends with crank arms 24 and 25 respectively, said arms projecting in opposite directions from said shaft. The crank arm 24 is loosely connected, through the instrumentality of a plurality of links 26, to the upper end of a weighted valve 27, said valve being cone-shaped at its lower end as shown at 28, said cone-shaped portion being adapted to fit snugly within the upper end of the pipe 7 for the purpose of preventing any carbide from being discharged from the hopper 3 until said valve is raised.

As seen in Fig. 3, the guide 20 is formed with a laterally extending boss 20' through which the inner end of the tube 21 projects into the interior of said guide, a nut 20'' being threaded on said inner end thus clamping the boss 20' securely between said nut and a second annular collar 21'' which is formed on the inner end portion of the sleeve 21. By this arrangement of parts, it will be seen that the guide 20 is rigidly supported within the hopper and that the outer end of the tube 21 acts as one member of a stuffing box.

When the valve 27 is seated, the crank arm 30 will extend upwardly at substantially an angle of 45° and the gas bell 2 will be supported by the pressure of the generated gas as will be hereinafter described. As the gas is exhausted from the interior of the bell, 35 and said bell gradually descends, it becomes expedient to provide means for automatically raising the valve 27, thereby allowing the fresh charge of carbide to descend through the pipe 7 and into the generating 40 chamber between the bottom 4 of the tank 1, and the partition 5 therein. For this purpose I employ a chain 29 or other suitable connection, between the outer end of the arm 25 and the loop or eye 14. Thus it will 45 readily be seen, that when the bell 2 descends, said chain will pull downwardly upon the arm 25, this movement rocking the shaft 23 and through the action of the crank arm 24 and the links 26, raising the valve 50 27 to allow a charge of carbide to drop into the pipe 7. By reference to Fig. 1, it will be seen that the only outlet from the generating chamber, is the pipe 7 and therefore all gas generated in said chamber must necessarily rise within said pipe. For the purpose of conducting the generated gas from 55 the interior of the pipe 7, to the house connection and to the interior of the bell 2, I provide a horizontal pipe 30 which extends 60 outwardly from the pipe 7 and passes through the upright wall of the tank 1, its outer end being in communication with a filter 31, the latter having a suitable nipple 32 to which the service pipe is connected. 65 Intermediate its ends, the pipe 30 is pro-

vided with an outwardly opening check valve 33 and with a valve 34 which may be employed for cutting off the flow of gas entirely, or for conducting it to any one of the number of discharge pipes (not shown). The pipe 30 is provided, between the check valve 33 and its outer end, with a depending pipe 35 which has its lower end turned inwardly as at 36, beneath the lower end of the bell 2 and rises as at 37, its upper end 70 discharging into the cylinder 13 carried by the top of the bell 2.

With the parts as above described, the operation of the device is as follows: The carbide hopper 3 is filled with carbide and the shaft 23 is rocked in such a manner as to cause the valve 27 to rise within the guide 20 and thereby allow a quantity of said carbide to descend through the pipe 7 and into the generating chamber between the bottom 4 and the partition 5, said chamber having been previously filled with water. The action of the water upon the carbide will produce the gas which will now rise through the pipe 7 and into the hopper 3. Since there is no outlet from the hopper, the gas is forced to travel through the pipe 30 and the valves therein and through the filter 31 to the service pipe. If certain of the burners, connected to said service pipe, are now 95 opened, some of the gas will of course flow through said service pipe and be discharged from said burners. The major part of the gas generated will, however, descend through the pipe 35 and will therefore be discharged 100 in the upper end of the gas bell 2, said bell being substantially filled with water from the tank 1. The gas within the bell 2 will now cause said bell to rise and will thus release all tension on the chain 29. The weighted valve 27 will now drop by gravity 105 to automatically check the descent of the carbide and consequently no more generation will take place until some of the gas within said bell has been exhausted and it again 110 descends.

By the provision of the outwardly opening check valve 33, it will be seen that the gas from the bell 2 is prevented from returning to the generating chamber through the pipes 35, 30 and 7.

For the purpose of removing the exhausted carbide or sludge, from the generating chamber, I provide a valved pipe 40 which communicates with a suitable suction pump 120 and with the interior of said generating chamber. The suction through the pipe 40, although removing the major part of said sludge, would not be sufficiently strong to reach all parts of said chamber. I therefore provide an agitating finger or rod 41 which lies upon the bottom 4 and is provided with an upright operating rod 42 which passes revolvably through a tube 43, within the tank 125 1 and has its upper end turned laterally as 130

at 44 to provide a suitable operating handle. By the provision of this agitating means, the sludge upon said bottom 4, may be readily loosened and therefore the suction within 5 the pipe 40 will be sufficient to remove the same.

From the foregoing description, taken in connection with the accompanying drawings, the construction and operation of the 10 invention will be readily understood without requiring a more extended explanation.

Various changes in form, proportion and minor details may be resorted to without departing from the spirit of the invention as 15 claimed.

Having thus described my invention, what I claim as new and desire to secure by Letters Patent is:

1. An acetylene gas generator comprising an upright cylindrical tank having a horizontal partition near its lower end, the central portion of said partition being bulged upwardly, an upright gas discharge tube rising from said upwardly bulged portion 20 and communicating with the tank below the partition, a carbide hopper rigidly mounted on the upper end of said tube, a cylindrical gas bell having a central opening in its top loosely receiving said tube, a sleeve depending from the edge of said opening and loosely encircling said tube, said sleeve having an outwardly flared lower end positioned directly above the upwardly bulged portion of the partition, a valve in 25 the hopper, a crank on the exterior of the hopper for operating said valve, an upright cylindrical extension formed on and communicating with the interior of the gas bell, a chain connected to the upper end of said 30 extension and to said crank, a gas discharge pipe leading from the upper portion of said gas discharge tube through one side of said tank, a branch pipe leading downwardly 35 from said gas discharge pipe and located 40 between the bell and the water tank, said branch pipe extending inwardly beneath the edge of said bell and upwardly therein, the 45

extreme end of said pipe being located within 50 said cylindrical extension, and an outwardly opening check valve located between said branch pipe and the juncture of said gas discharge pipe with said tube.

2. In a device of the character described, a hopper having a cone-shaped lower end, a discharge tube in communication with the center of said lower end, a cylindrical guide located within said hopper and having its lower end spaced from said discharge tube, said lower end being open, a hollow boss formed on one side of said cylindrical guide, 55 a supporting tube having its inner end projecting through said hollow boss, a collar formed on said tube and in contact with the outer end of the boss, a nut threaded on the inner end of said tube, an internally threaded boss formed in the adjacent side of the hopper, the outer end of said tube being threaded into said boss and being formed with a stop collar contacting with the inner side of the hopper, a shaft projecting through 60 said supporting tube and having oppositely disposed cranks on its inner and outer ends, the innermost of said cranks being located within said cylindrical guide, a weighted 65 valve in said guide and adapted to close the opening in the lower end of the hopper, a connection between said weighted valve and the adjacent crank arm, a packing nut encircling the outer portion of said shaft and having a threaded engagement with the extreme outer end of the boss formed on said 70 hopper, a packing ring between the adjacent ends of said supporting tube and said packing nut, said adjacent ends being countersunk, and means in connection with the outermost of said cranks for oscillating said 75 shaft to actuate the valve.

In testimony whereof I have hereunto set my hand in presence of two subscribing witnesses.

HENRY O'MEARA.
